UNITED STATES PATENT OFFICE

2,337,298

HOSE NOZZLE

Samuel Nedbor, Dorchester, Mass.; Eunice N. Medoff administratrix of said Samuel Nedbor, deceased

Application May 9, 1942, Serial No. 442,285

3 Claims. (Cl. 299—129)

This invention relates to a hose nozzle of the type shown in my Patent 1,855,888, April 26, 1932. The hose nozzle illustrated in said patent comprises a nozzle member having a duct therethrough and a combined valve and spray device which is adjustable on said nozzle member so as to occupy either a position in which it closes the duct and thus acts as a valve device, or into a position in which it opens the duct and acts as a spray device to break up the stream of water into a spray. Such combined valve and spray device is also pivotally mounted and is capable of swinging laterally about its pivot into a third position in which it is entirely out of register with the duct so that the water will issue from the duct in a solid stream. In said patent, the adjusting movement of the combined valve and spray device is accomplished by the rotation of a sleeve which surrounds the nozzle member.

One of the objects of the present invention is to provide certain improvements in the nozzle described in my said patent by which, when the sleeve is operated to open the nozzle, the combined valve and spray device will be automatically turned on its pivotal connection and thus swung into its inoperative position in which position the duct is open for the discharge of the water as a solid stream.

A further object of the invention is to provide a simple means for adjusting the combined valve and spray device into its spray-forming position.

Other objects of the invention are to improve the hose nozzle described in said patent in various other ways which will be more fully set forth hereinafter.

In the drawings wherein I have illustrated a selected embodiment of the invention

Fig. 1 is a longitudinal section through a hose nozzle made in accordance with the invention and showing the nozzle in its closed position with the combined valve and spray device closing the duct.

Fig. 2 is a similar view showing the parts adjusted for forming a spray.

Fig. 3 is a similar view showing the combined valve and spray device in its inoperative position in which the water issuing from the nozzle is in the form of a solid stream.

Fig. 4 is an end view of Fig. 2 looking toward the left.

Fig. 5 is an end view of Fig. 3 looking toward the left.

Fig. 6 is a section on the line 6—6, Fig. 3.

Fig. 7 is a section on the line 7—7, Fig. 6.

Fig. 8 is a perspective view of the nut mem-

ber to which the combined valve and spray device is pivoted.

Fig. 9 is a perspective view of the retaining collar used in connection with the nut shown in Fig. 8.

Fig. 10 is a view of a supporting collar or ring adapted to receive a strap for supporting the nozzle from the shoulder.

Fig. 11 is a fragmentary sectional view showing a modified construction in which the valve 7 is provided with a soft seat.

The nozzle herein shown comprises a nozzle member 1 provided with an axial water-delivering duct 2 and having its base end 3 provided with interior screw threads 4 adapted to receive the exterior screw-threaded portion 5 of a hose 6.

The combined valve and spray device is indicated at 7. This device is shown as formed on the end of a stem 8 which is carried by two arms 9, each arm having the straight guiding portion 10 extending parallel to the axis of the duct 2 and the inclined portions 11 leading to the stem 8 and on which the stem is supported. If desired, the valve 7, stem 8, and arms 9 may all be made as an integral structure. The valve portion 7 is of a size to close the duct 2 by seating against a valve seat 12 at the end of the duct.

The inner ends of the arms 9 are pivotally connected to a nut member 13 which is screw-threaded to the nozzle member 1, the latter having the exterior screw-threads 14 for this purpose. Surrounding the nozzle member 1 is a controlling sleeve 15 which is capable of rotation on the nozzle member, said sleeve being shown as having a screw 16 extending therethrough, the inner end of which operates in a groove 17 formed in the nozzle member 1. This allows the sleeve to be rotated freely about the nozzle member but prevents any movement of the sleeve on the nozzle member in the direction of the axis thereof.

This sleeve 15 is formed with two grooves or guideways 18 in which the straight portions 10 of the arms 9 are received and operate. The inner ends of the arms 9 are shown as being provided with trunnions 19 that are received in recesses formed in the nut member 13, and since the straight portion of the arms 9 are received in the grooves 18, the turning of the sleeve 15 on the nozzle member will operate through the arms 9 to turn the nut 13 on the nozzle member and thereby move said nut axially on the nozzle member.

When the parts are in the position shown in Fig. 1 the valve 7 is resting against the valve seat

12, thereby closing the duct 2 and shutting off the nozzle.

When it is desired to use the nozzle, the sleeve 15 is turned on the nozzle member, thereby advancing the nut 13 from the position shown in Fig. 1 toward the right, and as the combined valve and spray device is carried by this sleeve, said device will be moved toward the right, thus opening the duct 2.

The device as thus far described is quite similar to that illustrated in my aforesaid invention, Pat. No. 1,855,888.

One feature of my present invention relates to novel means which act automatically as the sleeve 15 is turned to swing the combined valve and spray device on its trunnions 19 into a position entirely at one side of the duct 2 as shown in Fig. 3 so that the water will be delivered from the duct in a solid stream which is indicated by the dotted lines 20.

For this purpose, I have provided two spring pressed plungers 21 which are carried in recesses 24 formed in the nozzle member 1, which plungers act against the straight portions 10 of the arms 9. Each plunger is backed by a spring 25 and each spring and its plunger are retained in its recesses by the screw-threaded plug 26 as best seen in Fig. 7.

The nozzle element 1 is provided at its outer end with a stop collar 27 which is screw-threaded thereto and which serves to limit the outward movement of the nut 13.

One wall of each groove 18 is cut away at its outer end as shown at 28, the construction being such that when the nut member 13 has been moved to its outer limit as determined by the stop collar 27, the combined valve and spray device can swing about its trunnions 19 into the dotted line position Fig. 7 or full line position Fig. 3, thereby removing the valve member 7 entirely from the line of the duct 2.

When the sleeve 15 is turned to shift the nut member 13 and the combined valve and spray device toward the right from the position shown in Fig. 1 and said combined valve and spray device reaches the position shown in full lines Fig. 7, the springs 25 will operate automatically to swing the arms 9 laterally about their trunnions 19, thus swinging the valve device 7 out of register with the duct 2 as shown in full lines in Fig. 3. The springs 25 then function to retain the valve device in its inoperative position so long as the nut member 13 is in its extreme position against the stop member 27. This is an improvement over the construction shown in my Patent 1,855,888 because in said patent, there is nothing to hold the valve device in its inoperative position when the nut member is fully advanced, and if the nozzle of said patent were being used in connection with fire apparatus, the swinging movement of the nozzle to play the water on the fire would be apt to cause the valve member to swing from its inoperative position to its spraying position so that the stream of water delivered from the nozzle would be changing from a solid stream to a spray and back to a solid stream again due to the free swinging movement of the valve device resulting from a movement of the nozzle in directing the water to different portions of the fire. With my improvements, however, when the nozzle is first opened up, the springs 25 will ensure that the nozzle will deliver a solid stream of water and this solid stream will be maintained regard-

less of any movement which the fireman may give to the nozzle in playing water on the fire.

Another feature of my invention relates to a novel means for shifting the valve device from its inoperative position shown in dotted lines, Fig. 7 and in full lines Fig. 3 into its operative position to produce a spray as shown in full lines Fig. 7 and in Fig. 2.

The sleeve 15 has a guard sleeve 29 rotatively mounted thereon and this guard sleeve is provided with an inwardly directed finger 30 which is adapted to engage one of the arms 9 as the sleeve 29 is turned on the sleeve 15. As herein shown, the sleeve 15 is provided at its outer end with exterior screw-threads 31 which have screw-threaded engagement with interior screw-threads 32 with which the guard sleeve 29 is provided so that the guard sleeve 29 can be turned on the sleeve 15. The screw-threaded flange 33 of the guard sleeve is cut away as shown at 34 in Fig. 6 and the sleeve 15 is provided with a stop screw 35, the head of which operates in the said cut-away portion 34. This stop screw 35 permits a partial rotative movement of the guard sleeve 29 on the sleeve 15, the extent of such rotative movement being limited by the engagement of the screw 35 with the walls 36 of the cut-away portion 34. When the guard sleeve 29 is in the position relative to the sleeve 15 shown in Figs. 5 and 6, the finger 30 will be in its inoperative position so that as the combined valve and spray device is moved outwardly to the outer limit of its movement as shown by full lines Fig. 7, said device will be permitted to swing about its trunnions, thereby to place the valve 7 in its inoperative position shown in dotted lines Fig. 7.

The nozzle will then deliver a solid stream indicated at 20. If it is desired to change this solid stream into a spray, all that is necessary is to turn the guard sleeve 29 from the position shown in Fig. 5 to that shown in Fig. 4. During such turning movement, the finger 30 will engage one of the arms 9 and will swing the combined valve and spray device from its inoperative position shown in dotted lines Fig. 7 into its operative position in which the valve is in the axial line of the bore 2 but is spaced from its valve seat as shown in full lines Fig. 7 and as also shown in Figs. 2 and 4. The stream of water issued from the duct 2 will then engage the valve 7 and will be broken up thereby into the form of a spray as shown by dotted lines 43 in Fig. 2.

With the present improvements, the opening of the nozzle by rotating the sleeve 15 will automatically swing the combined valve and spray into its inoperative position whereby a solid stream will be delivered by the nozzle, and the change from a solid stream to a spray can be effected by simply turning the guard sleeve 29 through a slight angle to shift it from the position shown in Fig. 5 to that shown in Fig. 4.

The nut member 13 is shown as having two slots 37, one on each side thereof in which the trunnions 19 are received. These trunnions are retained in the closed ends of the slots by means of a retaining ring 38 which is screw-threaded to the screw-threaded portion 39 of reduced diameter with which the nut 13 is provided. This construction furnishes a simple means for assembling the combined valve and spray device with the nut 13 and of separating said device from the nut when it is necessary.

The guard sleeve 29 is shown as having a ring

40 of rubber encircling the same rod to provide an end grip by which said guard sleeve can be radially turned for the purpose of converting the solid stream delivered by the nozzle into a spray.

59 indicates a supporting ring mounted on the nozzle member 1 and adapted to turn freely thereon, said ring having an extension 54 provided with a slot 52 to receive a supporting strap by which the nozzle may be supported from the shoulder of a fireman.

In Fig. 11 there is shown a construction where-in a soft seat is provided for the valve 7. In this embodiment the nozzle member 1 is provided with a recess at its outer end in which is received a valve seat member 61 of rubber or some soft metal. This valve seat member is retained in place by the stop member 27a which, in this embodiment, is provided with the hub extension 60 having exterior screw threads that are adapted to engage interior screw threads formed in the end of the nozzle member 1.

I claim:

1. A hose nozzle comprising a nozzle member having a water-delivery duct and also having a valve seat at the delivery end of said duct, a combined valve and spray element mounted on the nozzle member for movement axially thereof between a position in which said combined valve and spray element is seated on said valve seat and thus closes the duct and a second position spaced from said valve seat and in line with said duct, in which second position said combined valve and spray element acts as a spray-forming element, said combined valve and spray element being movable laterally between its spray-forming position and an inoperative position out of line with said duct, manually operated means mounted on the nozzle member to give the combined valve and spray element said axial movement, springs so positioned as to give said combined valve and spray element said lateral movement upon completion of said axial movement, a sleeve carried by the nozzle member and having limited turning movement thereon, and a finger carried by said sleeve for engaging the combined valve and spray element and swinging it from its inoperative position into its spray-forming position.

2. A hose nozzle comprising a nozzle member

having a water-delivery duct and an exteriorly screw-threaded portion, a nut screw-threaded on said screw-threaded portion, a combined valve and spray element pivotally connected to said

5 nut, a sleeve rotatively mounted on the nozzle member and having means operatively connecting it to the nut and the combined valve and spray element in such a manner that the latter is confined to axial movement from the position 10 in which it closes said duct to a position in which it opens said duct and acts as a spray-forming element, springs so positioned as to move the combined valve and spray element about its pivotal connection to a position out of the line of discharge from said duct after said axial movement, and means mounted on said sleeve to turn about the sleeve axis for swinging the combined valve and spray element about its pivotal connection against the pressure of the springs from 15 its inoperative position into a position in line with the duct.

3. A hose nozzle comprising a nozzle member having a water-delivery duct provided with a valve seat at its end, said nozzle member having 20 an exteriorly screw-threaded portion, a nut screw-threaded on said screw-threaded portion, a combined valve and spray element pivotally connected to said nut, a sleeve rotatively mounted on the nozzle member and having means operatively connecting it to the nut and the combined valve and spray element in such a manner that the latter is confined to axial movement from the position in which it closes said duct to a position in which it opens said duct and acts 25 as a spray-forming element, springs so positioned as to move the combined valve and spray element about its pivotal connection with the nut to a position out of the line of discharge from said duct after said axial movement, a second 30 sleeve mounted on the first-named sleeve for limited rotative movement thereabout and a finger carried by said second sleeve and cooperating with the combined valve and spray element to swing the latter about its pivotal connection with 35 the nut from its inoperative position to the position in which it acts as a spray-forming element.

SAMUEL NEDBOR.
